[21] Appl. No.: 29/090,363

[57] CLAIM

[22] Filed: Jul. 7, 1998

The ornamental design for a "trim" icon for a display screen,
as shown and described.

[51] LOC (7) Cl. 14-02

DESCRIPTION

[52] U.S. Cl. D14/495

FIG. 1 is a front view of a "trim" icon for a display screen
according to the present invention, the broken line drawing
of a display screen is for illustrative purposes only and forms
no part of the claimed design; and,

[58] Field of Search D14/114, 114.1-114.9;
D18/24-33; D20/11; D19/6; 345/326, 339-40,
347-57; D21/324-33

FIG. 2 is a front view thereof, on an enlarged scale, the
"trim" icon is shown separately for clarity of illustration.
